UNITED STATES PATENT OFFICE.

HENRY MILLER, OF GRAFTON, WEST VIRGINIA.

VIOLIN MANDOLIN.

Application filed August 8, 1925. Serial No. 49,083.

This invention relates to inventions in musical instruments, especially violins, and has for its object to increase the volume of the musical notes emitted therefrom as well as to improve the timbre thereof. To this end the instrument which I have termed a violin-mandolin employs four double strings instead of the four single strings usually found on violins, and these strings are mounted over a sound box formed of a cocoanut shell which is entirely closed on the bottom and sides and has its open top closed by a cover provided with a small central aperture through which the amplified sounds may pass.

Other objects and advantages of the invention will be apparent from the following description when taken in connection with the accompanying drawings, in which:

20 Figure 1 is a perspective view of the improved violin-mandolin.

Figure 2 is a vertical section through the instrument, parts being broken away, and

Figure 3 is a bottom plan view.

25 Referring to the drawings more in detail, the numeral 1 indicates the musical instrument generally, while numeral 2 refers to the main frame on which the strings 3 are mounted.

30 The sound box of the violin-mandolin consists of a single cocoanut shell 4 which has imperforate bottom and sides, except as hereinafter indicated, and an open top 5. This open top is closed, however, by a wooden cover 6 provided with a central opening 7 through which the sounds may 35 pass from the interior of the sound box. The cover 6 is reinforced by means of metal bands or wires wound around its periphery and designated by numeral 8.

40 Two diametrically opposed sides of the shell 4 are apertured to receive the frame member 2 which passes therethrough and to which the base portion 9 and fingerboard 10 are attached. For the purpose of mounting the strings 3, which are eight in number and arranged in pairs, a tail piece 11 is anchored to the base portion 9 and has the strings 3 attached thereto in the usual manner. These

45 strings pass over a bridge 12 mounted over opening 7 in the sound box cover and are secured to the tuning keys 13 on the opposite end of the frame 2.

The violin-mandolin is provided with the conventional chin rest 14 and bow (not shown), and is reinforced by means of the stays 15 which are secured to the frame 2 adjacent the tuning end thereof, and passed through the guide 16 on the base of the cocoanut shell 4 before being attached to the adjusting screws 17 mounted on the base portion 9.

The instrument just described is played in exactly the same manner as an ordinary violin, but is a great improvement over the violin not only in the fact that the volume of sound is increased by the use of the double strings, but also in the fact that the timbre of the notes produced is greatly improved by combining the double strings with a sound box of the type specified.

20 In accordance with the patent statutes, I have described what I now believe to be the best embodiment of the invention, but I do not wish to be understood thereby as limiting myself or the scope of the invention, as changes and modifications may be made without departing from the spirit of the invention; all such I aim to include in the scope of the appended claims.

What I claim as new and desire to secure by Letters Patent is:

1. A musical instrument of the class described, including a sound box formed of a cocoanut shell closed at its bottom and sides, 35 a centrally apertured cover for the top of said shell, and a reinforcing band encircling the periphery of said cover.

2. A musical instrument of the class described, including a sound box formed of a single cocoanut shell having a closed bottom and sides and an open top, a frame member extending through said sound box intermediate the top and bottom thereof and an apertured cover for the open top of said sound box.

3. A musical instrument of the class described, including a sound box formed of a cocoanut shell having a closed bottom and sides and an apertured top, and four sets of 100 double strings mounted above said apertured top.

HENRY MILLER.
